UNITED STATES PATENT OFFICE.

CECIL THROCKMORTON, OF GLENNIES CREEK, NEW SOUTH WALES.

BURNER FOR OIL-LAMPS.

SPECIFICATION forming part of Letters Patent No. 623,443, dated April 18, 1899.

Application filed January 19, 1898. Serial No. 667,180. (No model.)

To all whom it may concern:

Be it known that I, CECIL THROCKMORTON, gentleman, a subject of the Queen of Great Britain, residing at Greylands, Glennies Creek, near Singleton, in the British Colony of New South Wales, have invented a new and useful Improved Burner for Oil-Lamps, of which the following is a specification.

This invention relates to an improved burner for oil-lamps, which though specially devised for lamps such as those for domestic purposes in which kerosene, paraffin, or like high-grade oil is used is yet applicable to all lamps in which hydrocarbon oils more or less easily vaporized are used.

This improved burner for oil-lamps consists of two main parts—a tip and a vaporizing-cell, the former forming the top of the latter, the bottom of which latter is in connection with an oil-reservoir. The tip is made of refractory heat-conducting material of more or less porous nature, such as plaster-of-paris or such as fire-clay or the like, mixed with combustible material, but out of which the said combustible material has been burned. This tip is perforated and is firmly fixed to the top of the vaporizing-cell, which vaporizing-cell is filled or nearly filled with fibrous or spongy material—such as tow, cotton-waste, or the like—or with other material which will split up or divide the oil.

In one construction of this improved burner, which is used when the oil-reservoir is above the level of the burner, the bottom of the vaporizing-cell is connected to said reservoir by a bent pipe having a regulating-tap or other device, such as a bird-fountain connection or other means, for regulating the amount of oil supplied through the bent pipe to the burner.

In a modified construction of this burner, which is used when the oil-reservoir is below the burner, as in ordinary hand or table lamps, the vaporizing-cell is affixed to the top of the wick-tube, and the ordinary wick terminates in the fibrous or spongy filling in said cell.

In order to the saving of the oil, to the prevention of the charring or burning of the filling material of the cell, and to the speedy extinguishment of the lamp, a movable head is

combined with the burner, adapted to stand clear of the tip and to closely fit over the tip when required to cut off the supply of oxygen thereto; but in order that this invention may 55 be clearly understood reference will now be made to the drawings herewith, in which—

Figures 1 and 2 are cross-sectional elevations at right angles, respectively, of one construction of this improved burner for oil-lamps specially devised for use on a lamp having the oil-reservoir above the level of the burner, and these views show the extinguishing cap or hood in position closed over the tip. Figs. 3 and 4 are a central sectional elevation and a plan, respectively, of a modified construction of burner for use on an ordinary hand or table lamp or a lamp having its oil-reservoir below its burner, and in these views the extinguishing cap or hood is shown as elevated clear of the tip, and in Fig. 4 the burner-cone is removed. Fig. 5 is an enlarged cross-sectional elevation of the burner; Fig. 6, a plan of the tip, and Fig. 7 a longitudinal elevation of the burner.

A is the tip; B, the vaporizing chamber or cell; C, the oil-supply pipe or wick-tube; D, an ordinary slotted burner-cone, and E an ordinary chimney gallery or support. The tip A, of refractory and porous material, has perforations A^X, as shown, medially of its length, and it has grooves A², into which spring the upper edges B² of the vaporizing-cell B, thus firmly holding it in position. The lower parts A³ of this tip extend downwardly, as shown, 85 into the filling B' of the vaporizing-chamber, said filling being of a fibrous or spongy nature, such as the materials before mentioned, or asbestos or any other material which will split up or divide the oil which enters the vaporizing-cell. In the burners shown in Figs. 1 and 2 this vaporizing-cell B is connected with branch pipes C' to the main supply-pipe C, which has a tap or valve C² or other contrivance for regulating the supply of oil to said 90 vaporizing-cell. In the construction of burner shown in Figs. 3 and 4 this vaporizing-cell B has an inset channel or socket B³, adapted to tightly fit over the top of the wick-tube, which wick-tube contains an ordinary wick C^X, as 100 shown, dipping into the oil-reservoir. On the side of the vaporizing-cell B is hinged at F'

the hood or cap F, and extending therefrom is a lever F², having a connecting-rod F³ to lever F⁴, terminating in thumb-piece F⁵.

In use (the regulating tap or valve of burner shown in Figs. 1 and 2 being turned on) the light is applied to the porous tip, when the oil contained therein burns and so heats such tip and its downward extensions A³, causing the oil in chamber or cell B to vaporize, and this escaping through the perforations A⁴ in the tip burns and emits a good and steady illuminating-flame. In extinguishing the lamp the thumb-piece F⁵ is pushed to operate lever F⁴, which operates rod F³ and lever F², causing the cap or hood F to fall over on its hinge F¹ and closely fit the tip A, and thus cut off the supply of oxygen and smother or extinguish the flame. In using the burners shown in Figs. 1 and 2 it is necessary to cut off the flow of oil to the burner by manipulating the tap or valve C² or other regulating contrivances.

It is to be understood that though I have shown what I consider to be the best constructions of this improved burner, yet I do not confine myself to the precise details described and illustrated so long as the nature of this invention be retained.

Having now particularly described and explained the nature of my invention and in what manner the same is to be performed, I declare that what I claim is—

1. In a burner for oil-lamps, the combination with the vaporizing-cell B, and a filling B' of fibrous or porous material placed in said cell, of the perforated refractory tip A having in its sides the grooves A³ into which are sprung the upper edges of the vaporizing-cell and provided on its under side with projections A⁴ that are extended into the filling in the vaporizing-cell, substantially as described. 40

2. In a burner for oil-lamps, the combination of the vaporizing-cell B having a filling B' of fibrous or spongy material, the perforated refractory tip A secured to the top of said cell and having projections A³ extended into the filling material, and a hood F hinged to one side of the vaporizing-cell and provided with lever mechanism, substantially as described. 45

Dated this 22d day of September, 1897.
CECIL THROCKMORTON.
